CHECK WRITING MACHINE

Herman C. Welter, Rochester, N. Y., assignor to
 Hall-Welter Co. Incorporated, Rochester, N. Y.,
 a corporation of New York

Application March 15, 1939, Serial No. 261,995

5 Claims. (Cl. 101—20)

My present invention relates to printing and more particularly to small portable devices, such as are used in business establishments for printing upon the designated line the cash amounts of checks. The invention has more particularly to do with check writing machines of this character in which a plurality of movable printing types are individually adjustable to collectively produce different amount combinations, such individual adjustment of the types being effected by hand levers or keys that the operator moves to a selected point with the aid of calibrations upon an outside scale. When the types have been so set a platen is brought into engagement therewith through the medium of a general operating member so that the printing act is accomplished in the pre-selected denomination. It is sometimes desired to repeatedly print checks of the same amount and it is at other times desired to change the amount printed on the check between operations.

It is the latter requirement with respect to which the present invention has to do and its general object is to provide a simple and effective means for restoring the individual types to a zero or neutral position so that after the operating member has performed its function the setting devices will be restored and, as in the previous setting, they may be moved to print a new and different amount when the general operating element is again brought into use.

More particularly, an object of the present invention is to provide a mechanism of this character of simplified construction in which a re-setting or clearing means for the type setting keys hugs the latter at all times so that, after the printing operation, it is motivated without impact and hence reduces the noise and wear incident to the actuation of such an element in structures where it is normally held in a far position and is then released or motivated to perform the clearing operation. To these and other ends, the invention resides in certain improvements and combinations of parts, all as will be hereinafter more fully explained, the novel features being pointed out in the claims at the end of this specification.

In the drawings:

Fig. 1 is a top plan view of a check writing machine constructed in accordance with and illustrating one embodiment of my invention;

Fig. 2 is a side elevation thereof viewed from the side of the main operating lever, namely, the right side;

Fig. 3 is a substantially central longitudinal

vertical section taken from front to rear and viewed from the same side as that of Fig. 2 but enlarged, the printing parts being in normal or inoperative position;

Fig. 4 is a view similar to Fig. 3 on the same scale partly broken away and directionally reversed, showing the printing couple in operative position, that is, with the operating handle actuated to produce an impression on the check;

Fig. 5 is a view similar to that of Fig. 4 further broken away but showing the type setting means in a different position of adjustment;

Fig. 6 is a view similar to Fig. 5 but showing the positions of the parts when the operating lever is actuated, Fig. 5 showing the latter in normal position;

Fig. 7 is a fragmentary detail front and top view, partly in section, of the key mechanism and the clearing yoke;

Fig. 8 is a fragmentary detail directionally reversed illustrative of the slip-off connection between the actuating element of the clearing device and the main operating element;

Fig. 9 is a bottom plan view of the machine, and

Fig. 10 is a vertical section from front to rear through the base thereof showing, in comparison with Fig. 2, the action of the vacuum cups in their function of holding the machine to the desk table or other support.

Similar reference numerals throughout the several views indicate the same parts.

A known check writing machine to which my present improvements are applicable is disclosed in my prior patent, No. 1,959,185, dated May 15, 1934. The general structure of that machine has been reproduced to some extent in the accompanying drawings and requires description herein only insofar as such description will aid in understanding the additions and improvements that I have now made. In this view and referring more particularly to the drawings and first to Figs. 1 and 2 thereof, 1 indicates a casing divided by a horizontal slot 2 into a lower base portion 3 and an upper housing or overhanging breast portion 4. The base portion 3 is provided with a table plate 5 constituting the bottom of the slot. In the printing of a check, the latter is laid upon the table, thrust back into the slot and by means of a pivoted back gauge arm 6 positioned so that with the aid of a pivoted line gauge 7 the printing impression through the devices hereinafter described may be accurately placed on the amount line of the check. This

is all preliminary explanation and old and familiar to those skilled in the art.

The printing couple is composed, in the present machine, of a plurality of movable types individually adjustable to produce, collectively, different amount combinations as in dollars and cents together with a single platen movable toward and from a printing line on which said types are selectively assembled. The types, in the sectional views, are indicated at 8 upon the peripheries of segments 9 mounted to turn upon a shaft 10, itself immovable in the upper casing 4. Its immobility is secured by an anchor rod 11 passing through arms 12 extending from fixed type members 13 pinned to shaft 10 at 14. These fixed type members bear such designations as "Exactly" or corresponding similar characters applicable to presentation in the printing line along with the changeable amount characters.

The platen element of the printing couple is indicated at 15 as being carried on a rock arm 16 pivoted on a shaft 17 mounted in the base portion 3. With the rocking of the arm, the platen is carried through an opening 18 in the table 5 to printing contact with the types 8 and 13 being retracted to the normal operative position of Fig. 3 by means of a spring 19. It is so actuated by a main operating lever 20 that has the normal position of Figs. 1, 2, 3, 5 and 9 and is pulled forwardly by the operator to the depressed position of Figs. 4 and 6 to effect the printing of the check. For this purpose, a toggle connection beginning with an arm 21 pinned to a main operating shaft 22 on which the operating lever 20 is carried and involving wrist pins 23 and 24 and a connecting link 25 imparts to the rock arm 16 the necessary printing pressure.

There are other connections beginning with a link 26 whereby the main operating lever and shaft actuate an inking mechanism but this is of no interest to the present invention and elements thereof and are illustrated in the accompanying drawings merely for the purpose of linking up the disclosure with that of applicant's before-mentioned check writing patent.

The type faces 8 before referred to as carried upon the carrier segments 9 embody successive numerals in the tens, hundreds and thousands digits of dollar designations and also numerals for the required cents digits. They are individually adjusted to collectively form a presentation of the desired amount at the printing point by keys 27 on the projecting ends of arms 28 extending from the carrier segments 9 and operating through slots 29 in the upper casing 4, as best disclosed in Fig. 1. Adjacent to the respective slots are scales 30 carrying a like system of numerals and, as will be at once understood, moving an individual key and arm to a corresponding numeral on that scale will bring the desired type numeral into printing position.

The type carriers are individually centered in their positions of adjustment by spring tensioned yielding pawls 31 (Fig. 4) engaging serrations 32 on separate upper segments thereof.

All of the foregoing is merely introductory as before indicated, to a description and understanding of the mechanism for resetting the type arms 28 and keys 27 to neutral or zero positions after the printing operation. They are shown in such zero positions in Figs. 1, 3 and 5, but Figs. 2 and 4 show one or more of them moved forwardly and downwardly to type selecting positions that they occupy while the impression is

being made. In the practice of my present invention, I mount freely upon the type shaft 10 the arms 33 of a yoke 34 that spans the casing from side to side in the path of the type setting arms 28. It may be of assistance to the reader to here state that in the sectional views no attention is to be paid to the fact that this yoke is shown apparently separate from the arms because, as a matter of fact, it is spot welded thereto and may, therefore, be regarded as an integral extension thereof.

Also pinned to the main operating shaft 22 is a plate or arm 35 having thereon a pin 36. Pivoted to one of the resetting or clearing yoke arms 33 at its forward end by means of a wrist pin 37 is a draw bar 38 adjacent to the right side of the casing 1. Except for the aforesaid wrist pin connection 37, this draw bar may be said to float. Adjacent to the wrist pin 37, there is mounted on a stud 38a on the casing of the machine a spring 39, the free end of which bears down upon the draw bar 38 and assists its own gravitational force in holding it in cooperation with companion parts hereinafter described. It will be obvious that the normal action of this spring is to press downwardly the rear end of the draw bar 38 which, unless restrained, rides upon the pin 36.

The said draw bar 38 has a special conformation on its under side. This includes a riding surface 40 terminating in a shoulder 41.

The left hand end of type shaft 10, as shown in Fig. 7, is encircled by a spring 57, one end of which is engaged with an arm 33 of the clearing yoke 34 at 58, while the other end reacts against a fixed post 59 on the inside of the casing wall 1. The tendency of this spring is to urge the yoke toward the stems or arms 28 of the type setting keys in that direction in which they are restored to neutral or zero positions. In other words, this spring 57 seeks to motivate the yoke in an operative or clearing direction with relation to the keys but it is not of sufficient strength to actually move them from the positions to which they are adjusted and in which they are held by the dogs 31.

As so far described, the mechanism acts as follows: The normal position of the clearing yoke 33-34 is that shown in Figs. 3 and 5 in abutting relationship with the key arms 28 and, when the latter are in neutral or normal zero position, with all of them. When a selected key is moved forwardly to position a connected type on the printing line, as, for instance, the key marked 28x in Fig. 7, it pushes the yoke ahead of it, displacing it a corresponding degree against the tension of its spring 57 in which position the yoke remains until a companion key is drawn forward a greater distance, whereupon the latter picks up the yoke and reacts correspondingly, and so on. A depression of the rear end of the draw bar 38 under the influence of its spring 39 tends to hold surface 40 thereof in the path of pin 36 on plate 35 of operating shaft 22. The depression of the rear end of draw bar 38 tends to hold surface 40 thereof in the path of pin 36 on plate 35 of operating shaft 22.

It is to be noted at this point that so far as the positive printing operation is concerned nothing happens with respect to the resetting mechanism last described on the mere forward movement of the operating lever 20 that effects the actual printing. On the other hand, it is

the return movement of this operating lever that accomplishes that result.

In the general operation of the machine, when the operating lever 20 is brought forward from the position of Figs. 1, 2, 3 and 5, it being assumed that appropriate types on the various segments 9 have been brought into the printing line opposite the impact of the platen 15, the latter is raised from the position of Fig. 3 to that of Fig. 4 in the ordinary manner through the mechanical connections previously described. This forward movement of the operating lever is an idle one so far as the draw bar 38 is concerned because the plate 35 on the same operating shaft 22 and its pin 36 is moving forwardly on the riding surface 40. The limit of the forward movement of such operating crank 20 is shown in Figs. 4 and 6. The arrival at this forward position results in the forward advance of pin 36 on member 35 on the operating shaft 22 and the dropping of draw bar 38 to the extreme low position of Fig. 4, incidentally bringing shoulder 41 on the draw bar in the direct path of such pin 36 on its return. When the latter so returns with the operating lever, it engages and interlocks with shoulder 41 on the draw bar, as shown in detail in Fig. 8, dragging the latter rearwardly and with it the clearing yoke 33—34 which it positively actuates in this respect. The result is that the clearing and resetting yoke picks up successively or simultaneously, according to their previous adjustment, all of the radial key levers 28 of the various type segments and thrust them back to the normal position of Figs. 3 and 5 augmented by the action of the yoke spring 57 or at least not opposed thereby. When such a sufficient actuation of the draw bar has been accomplished, the length of the riding surface 40 and its relation to the shoulder 41 in agreement with the movement of the pin 36 is such that just as the draw bar, through its wrist pin connection 37, carries the clearing yoke 33—34 to restore the type keys and levers to neutral position, the pin 36 rides below the shoulder 41 in the pin's downward and rearward movement and automatically disconnects itself from further affecting the attained result of restoring the keys and key arms with the clearing yoke 34 still mildly engaging the same under the impulse only of its own weak actuating spring 57. This is another way of stating that the draw bar 38 through its wrist pin connection 37 with the clearing yoke 33—34 disconnects from the latter when the same has restored the key and type arms to normal neutral or zero positions.

To positively disengage pin 36 from shoulder 41 of draw bar 38 at the conclusion of the effective movement of the latter on the return of the operating crank so that clearing yoke 34 will come to rest against the type setting arms 28 of the keys 27 in their neutral or zero position, there is also mounted on plate 35 carrying pin 36 a dog 42 in the form of an adjustable slotted plate secured by a screw 43 to a flange 44 bent laterally from the said plate, by means of which screw and slotted connection the dog 42 may be advanced radially from the axis of operating shaft 22. Surface 40 beforementioned on draw bar 38 lies in the path of this dog. The dog's projection, so regulated by screw 43, causes it to engage surface 40 and causes pin 36 on plate 35 to slip out of engagement with shoulder 41 on the draw bar at the proper point. The idea is that this adjustment shall be so made that pin 36 will keep positive contact with shoulder

41 on the draw bar until the latter has returned setting levers 28 to just the right point and thereupon totally relieve draw bar 38 from pin 36 so that the latter may ride under shoulder 41 and across an under surface 45 on the rear extremity of the draw bar. In other words, when the operating lever 20, on such an adjustment, moves forwardly to an extreme position, it merely accomplishes the printing operation. When it moves rearwardly, it picks up its actuator 38 otherwise idle and accomplishes the result stated.

It is sometimes desired to repeatedly print a number of checks of the same denomination, as, for instance, in a simple illustration, where a number of employees are being given a pay check of the same amount, say, \$25. In that case, it is obvious that the operator should not be required to reset the amount keys 27 back to \$25 after printing each check but should be allowed repeated actuation of the main operating lever to produce on successive checks replications of the same amount as may be required.

To take care of this, I provide a simple means for rendering the resetting yoke 34 inoperative at the will of the operator by temporarily holding draw bar 38 out of all contact with the operating mechanism on the return of operating lever 20 after the printing operation. This consists, in the present instance, of a dog 46 (Figs. 5 and 6) mounted to turn in a wall of the upper casing 30 on the right side of the machine adjacent the operating lever 20. Externally, it is provided with a finger piece 47 (Fig. 2) by means of which it may be adjusted by the operator between the positions of Figs. 2 and 5 and that of Fig. 6. On the interior, it has a laterally and inwardly turned flange 48 adapted to engage beneath the draw bar 40, heretofore described as "floating," and to throw it out so that it becomes ineffective. The action is as follows:

Where a resetting of the keys is desired, after each adjustment of the type elements, finger piece 47 is tilted forwardly, as in Fig. 5, throwing detent 48 entirely out of action. On the other hand, when the said repetitions of printing are to occur, finger piece 47 is rocked rearwardly to the position of Fig. 6. Thereupon when draw bar 40 moves under the influence of the operating lever in either direction, it is held raised against the tension of its spring 39 by the flange 48 of the dog and is rendered idle and ineffective so that the pin 36 on member 35 of the operating shaft 22 cannot reach the shoulder 41 and cause the draw bar to actuate the clearing yoke.

The rubber vacuum cup 60 shown attached to the base element 3 and floor plate 61 thereof in Figs. 9 and 10 are for the purpose of insuring such contact with a table or desk that the manipulations of the operating crank 20 will not disturb the position of the machine.

In a check writing machine provided with a clearing yoke constructed in accordance with my invention, the following points are to be noted: the clearing or resetting yoke at all times hugs the arms of the setting keys for the type segments; it is displaced or retarded by the keys as they are advanced or by the key that is advanced to the greatest degree and when such clearing yoke is picked up by the actuating devices connected to the main operating means, it makes no noisy impact with the key or key arms but is positively actuated from that point in the same direction that its individual spring 57 is normally urging it.

I claim as my invention:

1. In a check writing machine, the combination with a printing couple embodying a plurality of movable types individually adjustable to produce, collectively, different amount combinations, a platen movable toward and from a printing line on which said types are so assembled and a plurality of operating keys for said types selectively movable out of alinement with one another to effect such amount combinations on the said printing line, and means for so operating the platen, of a resetting device for the keys adapted to restore them all to a neutral position, means constantly urging said resetting device to remain normally in contact with the most advanced key, and actuating means connecting the said device with the operating means.
2. In a check writing machine, the combination with a printing couple embodying a plurality of movable types individually adjustable to produce, collectively, different amount combinations, a platen movable toward and from a printing line on which said types are so assembled and a plurality of operating keys for said types selectively movable out of alinement with one another to effect such amount combinations on the said printing line, and means for so operating the platen, of a resetting device for the keys adapted to restore them all to a neutral position, a spring normally urging said device toward the keys in a direction tending to clear the same and normally maintaining the resetting device in contact with the most advanced key, and actuating means for the device having a slip-off connection with the operating means to be motivated thereby on the return movement of the latter.
3. In a check writing machine, the combination with a printing couple embodying a plurality of movable types individually adjustable to produce, collectively, different amount combinations, a platen movable toward and from a printing line on which said types are so assembled and a plurality of operating keys for said types selectively movable out of alinement with one another to effect such amount combinations on the said printing line, and means for so operating the platen, of a resetting device for the keys adapted to restore them to a neutral position and comprising a yoke, a spring normally maintaining said yoke in a clearing position by maintaining the same in contact with the most advanced key, a draw bar pivoted to the yoke to actuate the same, and a device on the operat-

ing means arranged to temporarily engage and motivate the draw bar and then slip off from and release the same, said yoke being at all times in contact with one or more of said keys.

4. In a check writing machine, the combination with a printing couple embodying a plurality of movable type segments mounted to turn on a common axis and individually adjustable to produce, collectively, different amount combinations, a platen movable toward and from a printing line on which said types are so assembled, a plurality of operating keys for said types embodying radially extending arms on the segments selectively movable out of alinement with one another to effect such amount combinations on the said printing line, and means for so operating the platen, of a resetting device for the keys adapted to restore them to a neutral cleared position and comprising a swinging yoke spanning the paths of the key arms and adapted to be displaced by the contact of a key arm as the latter is advanced from neutral position in the setting of the types, means constantly urging said yoke to remain in contact with the most advanced key and actuating means for the yoke motivated by the operating means to restore the yoke and all of the keys to normal and neutral positions.

5. In a check writing machine, the combination with a printing couple embodying a plurality of movable type segments mounted to turn on a common axis and individually adjustable to produce, collectively, different amount combinations, a platen movable toward and from a printing line on which said types are so assembled, a plurality of operating keys for said types embodying radially extending arms on the segments selectively movable out of alinement with one another to effect such amount combinations on the said printing line, and means for so operating the platen, of a resetting device for the keys adapted to restore them to a neutral cleared position and comprising a swinging yoke spanning the paths of the key arms and adapted to be displaced by the contact of a key arm as the latter is advanced from neutral position in the setting of the types, a spring constantly urging the yoke against the most advanced of the key arms but of insufficient strength to alone displace the same, and actuating means for the yoke motivated by the return movement of the operating means to restore the yoke and all of the keys to normal and neutral positions.
